UNITED STATES PATENT OFFICE.

JOSEPH COLDWELL, OF NEWMARKET, NEW HAMPSHIRE, ASSIGNOR TO DRAPER CORPORATION, OF HOPEDALE, MASSACHUSETTS, A CORPORATION OF MAINE.

FEELER MECHANISM FOR LOOMS.

1,418,536.

Specification of Letters Patent. Patented June 6, 1922.

Application filed April 16, 1921. Serial No. 461,786.

To all whom it may concern:

Be it known that I, JOSEPH COLDWELL, a citizen of the United States, residing at Newmarket, in the county of Rockingham and 5 State of New Hampshire, have invented an Improvement in Feeler Mechanisms for Looms, of which the following description, in connection with the accompanying drawings, is a specification, like characters on the 10 drawings representing like parts.

This invention relates to feeler mechanisms for looms, and more particularly to that type of such mechanisms now commonly known as penetrating feeler mechanisms.

In the penetrating type of feeler mechanism, it is the usual practice to provide an impinging and a penetrating feeler which enter the shuttle on each detecting beat and 20 feel for the filling. When a working supply of filling is present on a detecting beat, the penetrating feeler enters the filling mass and then the impinging feeler engages the surface of the filling mass and the two are 25 moved frontwardly during the remaining portion of the lay advance.

One of the objects of the present invention is to improve feeler mechanisms of this type, and more particularly with respect to 30 the connection between the penetrating feeler and the actuator with which it cooperates in effecting replenishment of filling.

In the accompanying drawings:

Figure 1 is a perspective view of a feeler mechanism embodying the present invention, some of the parts being broken away;

Fig. 2 is a sectional side elevation of the feeler mechanism, showing its action when the filling is substantially exhausted on a 40 detecting beat; and

Fig. 3 is an enlarged detached detail, showing the positive connection between the penetrating feeler and the adjusting bolt carried by the actuator.

The feeler stand 1 is provided with a cap piece 2, and the base and cap-piece are connected by screws 3. Extending longitudinally of the flanges 4 is the slot 5 through which passes the adjusting screw 6 for adjustably connecting the feeler stand to the 50 loom frame.

At one side of the feeler cap is the guide 7 into which extends the end of the transmitter 8 for initiating replenishment of fill-

ing through a train of mechanism well understood in the art.

Between the cap 2 and base 1 of the feeler stand is the slide 9, the front end portion of which has extending frontwardly the stem 10. A spring 11 surrounds the stem 10 and normally acts to maintain the feeler slide 9 in its rearward feeling position. A bridge 12 extends laterally of the feeler between the cap and base, and has an upwardly-extending lug 13 which, when the feeler is in its rearward position, serves to move the end 60 of the transmitter 8 rearwardly into the position for engagement with the actuator, as will presently appear.

The slide 9 is preferably slotted longitudinally at 14, and extending transversely of the slide is the pivotal support 15 on which is mounted the actuator 16, the front end portion of which is fan-shaped, as at 17, to engage the end of the transmitter when 75 the filling is to be changed.

A spring-actuated pin 18 mounted on the feeler stand below the actuator serves to normally hold the actuator in its raised or inactive position as indicated in Fig. 1. 80

The rear end portion of the slide 9 is provided with the elongated impinging feeler member 19 which serves to engage the mass of filling in the shuttle when a working supply is present on a detecting beat. The impinging head 19 of the feeler is slotted or cut away at 20, and through the narrow bearing between the impinging face of the impinging feeler and the cut-away portion 20, is a bearing 21 through which extends 90 the penetrating feeler 22, the construction being such that the penetrating feeler 22 may be loosely engaged with the bearing 21 and capable of longitudinal or rocking movement therein, the side walls 23 of the cut-away portion serving as stops for limiting the turning movement of the penetrating feeler. The rear end portion of the penetrating feeler 22 is provided with a penetrating edge or point 24 which is designed to enter the 95 mass of filling on a detecting beat between the coils thereof.

Adjustably connected to the actuator 16 is the screw 25, the head of which is positively connected to the end of the penetrating 100 feeler. The front end portion of the penetrating feeler is provided with a ball 26, which is seated in a socket 27 formed in the

head of the adjusting screw, and the rear edge portions of the socket 27 at 28 are in-turned to enclose the ball 26, and form a positive articulating connection between the 5 penetrating feeler and the actuator, the construction being such that movement of the penetrating feeler and actuator is effected positively and conjointly in both directions.

The positive connection between the actuator 10 and penetrating feeler not only insures conjoint movement of the feeler and penetrating member in both directions, but prevents disengagement of such connection by means of the inturned edges 28 of the 15 socket around the ball on the end of the feeler during the quick action of the feeler under the forward blow of the advancing lay.

It is desirable that the filling engaging 20 end of the penetrating feeler have sufficient freedom of movement to permit it to move laterally slightly and to turn slightly about its longitudinal axes. Such freedom of movement permits the penetrating feeler more 25 readily to enter between adjacent coils of filling upon the filling carrier. In the present construction the relatively short bearing 21 through which the penetrating feeler 22 loosely extends in connection with the ball 30 26 and cooperating socket at the front end of the penetrating feeler, support the feeler with the desired freedom of movement, while the feeler is maintained positively connected to the actuator 16. The penetrating feeler 35 is shown as supported so that the bent intermediate portion of the feeler is permitted a limited rocking movement relative to the supports for the ends of the feeler.

The shuttle 29 carries the usual filling carrier 40 or bobbin 30, and its front wall is slotted at 31 for the entrance of the impinging and penetrating feelers on a detecting beat.

When a working supply of filling is present 45 in the shuttle on a detecting beat, the normally projecting rear end of the penetrating feeler first enters the mass of filling or sinks into it between the coils thereof, and then the surface of the filling meets the 50 impinging feeler and the feeler members are moved forwardly together against the normal action of the spring 11. When, however, the filling is substantially exhausted on a detecting beat, the penetrating feeler 22 55 will be engaged by the more dense surface of the filling carrier or bobbin and forced forwardly relative to the impinging feeler, thereby moving the actuator into operative position, substantially as indicated in Fig. 2, 60 by depressing the front end portion of the actuator into a position for engagement with the end of the transmitter 8 as the two feelers and slide 9 are moved forwardly, to thereby effect replenishment of filling.

Since the front end of the penetrating 65 feeler is in positive connection with the actuator, manipulation of the adjusting screw 25 in either direction, effects corresponding adjustment of the end of the penetrating feeler with respect to the face of the impinging feeler, and a delicate relation of the end of the penetrating feeler and the impinging face of the impinging feeler is readily effected. When the screw 25 has been adjusted, it may be located in position by a lock 70 nut 32.

What is claimed is:

1. In a feeler mechanism for looms, the combination of an impinging feeler, a penetrating feeler which passes loosely through 80 the impinging feeler, an actuator, a ball and enclosing socket connection between the impinging feeler and actuator which positively connects the two and prevents disengagement 85 of the feeler from the actuator means engaging the ball and positively holding it in the socket.

2. In a feeler mechanism for looms, the combination of an impinging feeler, a penetrating feeler which passes loosely through 90 the impinging feeler, an actuator, a ball formed on one end of the penetrating feeler, an adjusting screw formed with a socket the edge walls of which enclose the ball and form a positive connection between and prevent 95 disengagement of the penetrating feeler and actuator.

3. In a feeler mechanism for looms, the combination of a penetrating feeler, an impinging feeler having a bearing for loosely 100 supporting the rear end of the penetrating feeler and adapted to permit a limited rocking movement of the forward end of the penetrating feeler relative to said bearing as a pivot, an actuator, a ball and enclosing 105 socket connection between the impinging feeler and actuator which positively connects the two and prevents disengagement of the feeler from the actuator.

4. In a feeler mechanism for looms, the combination of a penetrating feeler, an impinging feeler having a bearing for loosely supporting the rear end of the penetrating feeler, an actuator, a ball formed at the forward end of the penetrating feeler, means 110 upon the actuator having a socket receiving said ball and having edge portions for positively holding the ball within the socket and forming a positive connection for preventing disengagement of the feeler and actuator, said bearing and socket being constructed and arranged to support the penetrating feeler to permit a limited rocking movement 115 of the intermediate portion of the feeler.

In testimony whereof, I have signed my 125 name to this specification.

JOSEPH COLDWELL.
